Primary Examiner — Thomas Johannes*Assistant Examiner* — Samantha Q Lawrence(74) *Attorney, Agent, or Firm* — Brinks Gilson & Lione(57) **CLAIM**

The ornamental design for a pattern for an tissue sheet, as shown and described.

DESCRIPTION

The sole FIGURE is a top plan view of a tissue sheet, showing our new design.

The broken lines illustrate a boundary and forms no part of the claimed design.

The thickness of the tissue sheet forms no part of the claimed design.

1 Claim, 1 Drawing Sheet(56)
